John Thompson
ATTORNEY

UNITED STATES PATENT OFFICE.

JOSHUA HEUYARD, OF TERRE HILL, PENNSYLVANIA.

REPAIRING AND STRETCHING LAST.

1,016,827.

Specification of Letters Patent.

Patented Feb. 6, 1912.

Application filed April 15, 1911. Serial No. 621,246.

To all whom it may concern:

Be it known that I, JOSHUA HEUYARD, a citizen of the United States, residing at Terre Hill, in the county of Lancaster and State of Pennsylvania, have invented certain new and useful Improvements in Repairing and Stretching Lasts, of which the following is a specification, reference being had therein to the accompanying drawing.

10 This invention relates to a boot last and stretcher, of that class which is intended for repair work as well as for stretching the shoes, and constitutes an improvement over the device shown in my application filed

15 June 13, 1910, Serial Number 566,473.

The objects of the invention are to provide a stretcher and last of this kind that is so constructed and operated that the shoe is stretched evenly from the toe to the heel—
20 as the two halves of the last are forced apart in a parallel manner to each other.

Another object of the invention is to provide a last and stretcher of this class that will be cheap, durable, effective, and contain
25 few parts.

With these and other objects in view, my invention consists in certain construction and combination of parts as will hereinafter be fully described and claimed and illustrated in the accompanying drawings, which form a part of this application, and in which like figures of reference refer to corresponding parts in all of the views; but it is fully understood that while I have here described
30 my invention as shown, that I do not confine myself to the exact design as shown, as slight changes may be made in the construction and arrangement of the several parts without departing from the spirit of the invention.

In the drawings:—Figure 1, is a top plan view of my improved combined last and stretcher. Fig. 2, is a longitudinal horizontal sectional view. Fig. 3, is a sectional view of the last, showing the same open, and the heel block with the gear case cap removed. Fig. 4, is a longitudinal vertical sectional view, showing the working parts.

Referring to the drawings, the last is formed of two halves 1, and 2, which are held together in a flexible manner by the springs 3, and 25, which have one of their ends secured to one-half of the last, and the other end secured to the other half of said last by the pins 23, and 26, and which normally retain said halves in contact with each

other. Each of the halves or movable members 1, and 2, has the inner or abutting face provided with a longitudinal extending groove 4, which extends from the rear end 60 of and terminates at a point removed from the forward end of the members. The groove 4, near the center, is formed with an enlarged portion 5, which has the tapered or beveled ends 6, and 7. Mounted in the 65 groove 4, and enlargement 5, is a sliding member 8, which is formed with the wedge-shaped forward end 9, and the tubular rear end portion 10, which is screw-threaded to engage the forward end of the shaft 11. 70

Within the heel block 12, is mounted a gear case 13, within which is contained the bevel gears 14, and 15. The gear 15, is secured upon the rear end of the shaft 11, which extends through the hole 16, in said 75 heel block 12. The bevel gear 14, is adapted to rotate the gear 15, and shaft 11, by the action of a detachable wrench or key 17, which is provided with a squared end 18, for engaging a squared hole 19, in the top 80 of said gear 14. Said gear case 13, is retained within said heel block 12, by the plate 20, and screws 21, and also by the threaded collar 22, which is secured upon the end of the shaft 11. The plate 20, is formed 85 with a projecting forward portion 24, which is adapted to slide upon the rear portion of the upper surface of the last members 1, and 2, for the purpose of preventing them from swinging sidewise or turning upon the 90 shaft 11.

The device, in a closed position, having been inserted into the shoe, and the key then operated to revolve the gears, the last is first moved away from the heel until the 95 toe of the last has reached the toe of the shoe, when the last and heel cannot be further separated, but as the member 8, is still advanced by the shaft 11, its forward wedge-shaped end 9, engages and slides upon the 100 beveled grooves of the last, thus forcing the halves of the last apart from each other, and as the two halves of said last are flexibly joined together, they will exert an even stretch upon the shoe. 105

Having thus described my invention what I claim as new and desire to secure by Letters Patent is:—

In a combined shoe last and stretcher of the class described, the combination of a heel 110 member and a divided last member, having means mounted therein for spreading the

halves of said divided member, of a guide plate secured upon the upper surface of said heel member and provided with an extending portion adapted to slide upon the upper surface of the rear portion of the divided members, to prevent their turning with respect to said heel member.

In testimony whereof I affix my signature in presence of two witnesses.

JOSHUA HEUYARD.

Witnesses:

JOHN J. THOMPSON,
Wm. J. COULTER.
